Primary Examiner — Jennifer Rivard*Assistant Examiner* — Jennylou M Binas(57) **CLAIM**

The ornamental design for an ultrasonic cleaner, as shown and described.

DESCRIPTION

FIG. 1 is a top, front and right side perspective view of an ultrasonic cleaner showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1; and,

FIG. 11 is an enlarged view of portion 11 in FIG. 1. The broken lines in the drawings illustrate portions of the ultrasonic cleaner which form no part of the claimed design.

1 Claim, 11 Drawing Sheets(56)
